CLAIM

The ornamental design for an air freshener device, as shown and described.

DESCRIPTION

FIG. 1 is a left, top perspective view of a complete air freshener device;
FIG. 2 is an elevation view of the front thereof;
FIG. 3 is an elevation view of the back thereof;
FIG. 4 is an elevation view of the right side thereof;
FIG. 5 is an elevation view of the left side thereof;
FIG. 6 is a plan view of the top thereof; and,
FIG. 7 is a plan view of the bottom thereof.
